UNITED STATES PATENT OFFICE.

EVALENA S. THOMAS, OF LINDENWOLD, NEW JERSEY.

DESIGN FOR A TILE.

SPECIFICATION forming part of Design No. 28,670, dated May 17, 1898.

Application filed April 5, 1898. Serial No. 676,589. Term of patent 14 years.

To all whom it may concern:

Be it known that I, EVALENA S. THOMAS, a citizen of the United States, and a resident of Lindenwold, State of New Jersey, have invented and produced a new and original Design in Tiles, of which the following is a specification, reference being had to the accompanying drawings, which illustrate, in—

Figure 1, a perspective view, and in Fig. 2 a plan view, of the said tile.

The leading feature of my design consists in the respective edges of a four-sided flat tile being drawn on a compound curve in concavo-convex lines, as the edges *a*, *b*, *c*, and *d*, the opposite portions of the oppositely-disposed edges being concave and convex, respectively—viz., the convex portion of the edge *a* being practically opposite the concaved portion of the edge *b*, and the convex portion

of the edge *b* being practically opposite the concaved portion of the edge *a*, which is also true of the lines of the oppositely-disposed edges *c* and *d*, thus forming a four-sided tile with compound curved edges, the oppositely-disposed edges being drawn on lines substantially equal to each other.

Having thus described my invention, what I claim, and desire to secure by Letters Patent, is—

The design for tile substantially as herein illustrated and described.

In witness whereof I have hereunto set my hand this 31st day of March, A. D. 1898.

EVALENA S. THOMAS.

Witnesses:

THOS. F. GROSS,
MAUD THOMPSON.
